UNITED STATES PATENT OFFICE.

SIMON HEITER AND SALOMON J. LESEM, OF NEW YORK, N. Y.

DESIGN FOR AN UMBRELLA-HANDLE.

SPECIFICATION forming part of Design No. 11,695, dated March 23, 1880.

Application filed February 5, 1880. Term of patent 34 years.

To all whom it may concern:

Be it known that we, SIMON HEITER and SALOMON J. LESEM, citizens of the United States, and both residing at New York, in the county and State of New York, have invented and produced a new and original Design for Parasol and Umbrella Handles, of which the following is a specification, reference being had to the accompanying drawing, forming part thereof.

Our invention is designed to produce a novel and elegant design for the handles of umbrellas, parasols, &c.; and it consists in branching the head of the handle and surmounting the same with a series or chain of bead-like ornaments.

The accompanying drawing represents a side view of our design.

a is the body of the handle, preferably round in form, and with or without ornamentation, as desired. *b* is a branch springing out from the head of the handle, nearly flat in general contour, and having a curvature of about a quadrant of a circle. Surmounting this branch are bead-like ornamentations *c c c*, &c., which have the effect of a chain of balls, the whole presenting to the eye, when viewed from the side, a coronal appearance.

The bead-like ornaments *c c*, &c., may be

plain, as shown, or carved to give a more elegant and finished effect. In order to produce a more delicate and open-work design, they may be slightly tapering on their lower portions, as shown at *d d*, &c.

The branch and ornamentation may be of the same material as the body of the handle, or one or both may be made of such other material as will contrast strikingly or pleasingly with the general part of the handle.

We claim—

1. The design for an umbrella or parasol handle, which consists of a curved branch spreading out from the head of the handle and surmounted by a chain or series of bead-like ornaments, substantially as described, and shown in the accompanying drawing.

2. The design for an umbrella or parasol handle, which consists in a series of bead-like protuberances formed on a curved branching head, the outline of the whole presenting a coronal effect, as described, and shown in the accompanying drawing.

SIMON HEITER.
SALOMON J. LESEM.
